SUCTION CLEANER NOZZLE AND ADJUSTABLE BRUSH THEREFOR

Eugene F. Martinet, Cleveland, Ohio, assignor to
The P. A. Geier Company, Cleveland, Ohio, a
corporation of Ohio

Application March 23, 1937, Serial No. 132,556

8 Claims. (Cl. 15—158)

My invention relates to suction cleaner nozzles and adjustable brushes therefor in which are provided more than two positions or conditions of adjustment of the brush with respect to the

5 nozzle.

In a suction cleaner nozzle having an adjustable brush with more than two positions or conditions of adjustment of the brush with respect to the nozzle, it has been usual to provide for 10 three or more positions or conditions of adjustment of the brush with respect to the nozzle, which, if the number of selective positions or conditions of adjustment be three, may be a locked up position, a floating position or condition, and a locked down position, the several positions or conditions of adjustment of the brush being attained by manipulation of an operating member by the user of the suction cleaner.

In such a cleaner with three brush positions or 20 conditions of adjustment, having usual means associating the operating member with the adjustable brush, difficulties have been encountered in easily and certainly changing the position of the brush from the locked up position to the floating position or condition, the tendency being in manipulating the operating member to go past the floating position thereof and into the locked down position, which in most cases causes the suction cleaner brush to operate unsatisfactorily 25 on floor coverings, because the locked down position of the brush is only intended to be used on rugs having long naps or where there is a great deal of dirt or litter to be cleaned.

The objects of the present improvements include the provision of an improved suction cleaner nozzle and an adjustable brush therefor, and in which the brush may have three positions or conditions of adjustment with respect to the nozzle, two of which are attainable by reverse 30 thrusts of an operating member, and the third requiring for its attainment the application of a force first at an angle to the direction of the thrust followed preferably by a further thrust, whereby the brush may be normally positioned 35 either in a locked up position or a floating position or condition with respect to the nozzle by simple direct thrusts of the user's foot or hand, and whereby the locked down position of the brush with respect to the nozzle may be attained 40 by the application of a lateral or twisting and then a thrust movement of the user's hand applied to the operating member.

Further objects of the improvements include the provision of an improved suction cleaner 50 nozzle and adjustable brush therefor having a

simple and efficient arrangement of parts permitting economical manufacture and convenience in use.

The foregoing and other objects are attained by the nozzles, brushes, associations of nozzles and brushes, parts, combinations, and sub-combinations, which comprise the present invention, and the nature of which is set forth in the following general statement, and preferred embodiments of which are set forth in the following description, and which are particularly and distinctly pointed out and set forth in the appended claims forming part hereof.

The nature of the improved adjustable brush construction hereof, preferably incorporated in an improved suction cleaner nozzle and adjustable brush construction, may be stated in general terms as including brush mounting means preferably in the form of a cam and latch plate having cam and latch faces formed therein, and the brush mounting means is preferably secured upon preferably the rear wall of the nozzle of a suction cleaner.

A brush is mounted for upwards and downwards slidable movement, and preferably rocking 25 slidable movement on the mounting means, and an operating member is operatively associated with the brush and the mounting means for selective positioning of the brush with respect to the mounting means and thus with respect to the 30 nozzle.

The operating member is arranged for selective normal thrust movements between two positions, and also for selective additional movement between one of the first two positions and a third 35 position, the movement of the operating member between the first two positions serving to alternately position the brush with respect to the nozzle in two different positions which may be locked up position and floating position or condition, and the additional selective movement of the operating member between one of the first two positions and the third position serving to selectively position the brush with respect to the nozzle in a third position which may be locked 40 down position.

The position of the operating member corresponding to the floating position or condition of the brush is preferably determined by stop means, and the operating member is preferably mounted 50 on the brush for slidable and for pivoting and then slidable movement on the brush in passing between its several positions, and the operating member is preferably provided with cam follower and latch tongue means for cooperation with the 55

cam and latch faces of the preferred plate mounting means.

By way of example, embodiments of the improved nozzle and adjustable brush and parts thereof are illustrated as applied to a portable suction cleaner in the accompanying drawings forming part hereof, in which

Fig. 1 is a fragmentary side elevation of a portable suction cleaner including embodiments of the improved nozzle and adjustable brush and associated parts of the present improvements;

Fig. 2, an enlarged fragmentary view similar to Fig. 1, illustrating the relative positions of the nozzle and preferably rocking brush and associated parts, during a rearward movement of the suction cleaner nozzle;

Fig. 3, an enlarged elevation view looking in the direction of the arrows 3-3, Fig. 1 of the nozzle and brush and associated parts of the cleaner of Fig. 1, the brush and associated parts being mounted on the nozzle, and the nozzle being removed from the cleaner of Fig. 1, and the nozzle and brush and associated parts being shown in their relative positions when the brush is in floating position with respect to the nozzle;

Fig. 4, a sectional view as on line 4-4, Fig. 1, illustrating the mounting and adjusting parts for the brush, and the brush, in their relative positions with respect to each other, when the brush is in floating position with respect to the nozzle;

Fig. 5, a fragmentary plan sectional view thereof as on lines 5-5, Figs. 1 and 4, the brush being in the same floating position as in Fig. 4;

Fig. 6, a view similar to Fig. 4 in which the brush is in its relative position with respect to the other parts when the brush is in locked up or retracted position with respect to the nozzle;

Fig. 7, a view similar to Fig. 5, showing certain of the parts when the brush is in locked up or retracted position;

Fig. 8, a view similar to Fig. 4, but showing the brush in its relative position with respect to the other parts when the brush is in locked down or extended position with respect to the nozzle; and

Fig. 9, a view similar to Fig. 5, showing certain of the parts when the brush is in locked down position.

Similar numerals refer to similar parts throughout the several figures of the drawings.

A portable suction cleaner 10 is shown in Fig. 1, and includes a fan casing 11, in which is mounted a fan driven by a motor mounted in the motor housing 12, the fan casing and motor housing being mounted on forward wheel means 13 and preferably adjustable rear wheel means 14, and a usual pivoting handle 15 is provided for use by the operator in pushing and pulling the cleaner 10 on the wheels 13 and 14 back and forth over a surface being cleaned.

A usual dust bag 16 is connected to the exhaust side of the fan casing 11, and a nozzle 17 having walls forming an air duct therethrough is detachably connected by suitable means 18 with the inlet side of the fan casing 11.

The nozzle 17 forms part of the improved nozzle and adjustable brush and associated parts of the present improvements indicated generally by 19, and which also include a brush indicated generally by 20 operatively carried by mounting and adjusting means indicated generally by 21 which are secured upon the rear forwardly and downwardly sloping wall 23 of the nozzle 17, the wall 23 being at an angle to the

substantially horizontal plane of the entrance mouth 24 of the nozzle 17.

The nozzle 17 as shown is laterally elongated as is usual in portable suction cleaners, and the brush 20 as shown includes an elongated back member 25 from which extend downwardly bristle tufts 26.

The elongated brush back 25 may be made of wood, and as shown is engaged in the longitudinal trough opening of an elongated U metallic sheath case 27.

The brush mounting and adjusting means indicated generally by 21 includes an elongated mounting and cam plate 28 which is secured to and rearwardly spaced from and substantially parallel with the rear wall 23 of the nozzle 17, as by screw and spacer means 29.

The brush 20 is preferably rockably mounted for upward and downward adjustable positioning on the plate 28 as by means of screws 30 each having a shank 31 extending through suitable registering apertures in the brush back sheath case 27 of the brush back 25 and each extending through a registering upwardly and downwardly extending slot 32, one slot 32 being formed in the plate 28 for each shank 31; and preferably for permitting rocking of the brush 20 a shouleder collar nut 33 is screwed on each screw shank 31 with its enlarged shoulder head 34 at the front side of the plate 28 and with its collar shank 35 extending with clearance through its slot 32 and preferably screwed against washers 36 interposed between the collar nut 33 and the brush sheath case 27, there being clearance not only between the collar shank of each nut 33 and its slot 32, but also between the head 34 of each nut 33 and the washers 36 and the adjacent faces of the plate 28, as best shown in Figs. 2 and 5, thereby permitting rocking of the brush 20, as shown in one direction in Fig. 2, whereby the brush is rendered self-cleaning.

The plate 28 at the central portion of its upper edge is provided with a rearwardly extending tongue 37 upon which is secured the central portion of a downwardly pressing bowed leaf spring 38 having outer ends 39 having slots 40 formed therein through which extend the shanks of screws 41 which are screwed through suitable apertures in the brush back sheath case 27 and into the brush back 25.

The resilient leaf spring 38 serves to normally urge the brush 20 downwardly towards the nozzle mouth 24 and the surface over which the cleaner is being used, and when in use and when the brush 20 is only under the influence of the spring 38 it moves upwards and downwards and rocks in the slots 32 of the plate 28 and is in the floating position with respect to the nozzle.

The selective thrust placement of the brush 20 in the floating position or the locked up position, and the double movement placement of the brush 20 in the locked down position is attained by the construction and arrangement of parts now to be described.

The mounting and cam plate 28 has formed therein preferably two laterally spaced sloping brush raising cam faces 42 each connecting at its upper end with an up-locking upwardly presented latch face 43. Each cam face 42 and 43 may be as shown a portion of the periphery of an upwardly opening notch 44 formed in the cam plate 28 and each of which also includes a down-locking downwardly presented latch face 45 which connects with the lower end of a sloping brush lowering cam face 46.

5 A cam follower and latch hook operating member 47 is operatively interposed between the brush 20 and the cam plate 28, and is preferably provided at its outer end with an upwardly extending actuating tongue 48, whereby opposite lateral thrusts applied to the tongue 48, as by the foot or hand of the user, serves to alternately position the brush 20 with respect to the nozzle in the locked up position or float position, and 10 whereby after float positioning of the brush, a combined twist and additional thrust on the tongue 48 serves to position the brush 20 in the locked down position, or in other words the brush 20 is normally alternately selectively positioned only between the locked up and floating position, which are the two positions generally used, and the locked down position is only attained by a special action of the user.

20 The operating member 47 as shown is formed from an elongated preferably metallic flat strip, and is arranged to reciprocate, and also to reciprocate and slightly pivot, adjacent the upper face of the brush case 27.

25 For this purpose the strip member 47 has formed therein adjacent its inner end a laterally elongated straight slot 49 through which extends the shank of a headed screw 50 which screws through a suitable aperture in the brush sheath case 27 into the brush back 25.

30 Adjacent the actuating tongue 48 of the strip operating member 47, there is formed therein a slot 51 having laterally spaced and stop ends 52 and 53, and sides extending between the slot ends 52 and 53, and including straight opposite side portions 54 and 55 extending from the slot end 52 and straight opposite side portions 56 and 57 extending from the slot end 53, the slot side portions 52 and 53 being offset from the slot side portions 56 and 57 and being connected respectively therewith by angled stop or detent portions 58 and 59, and one of the headed screws 41 which extends through one of the end slots 49 of the spring 38 has its shank also extending through the slot 51.

45 The strip operating member 47 is also provided with two laterally spaced cam follower and latch catch tongues 60 extending rearwardly from the rear edge thereof, as shown, substantially at right angles to the cam plate 28, and each into one of the notches 44 thereof, for selective non-engagement or engagement with the cam faces and latch faces thereof, as hereinafter set forth.

50 A brush position designating plate 61 is preferably provided at one end of the top of the brush sheath case 27 and bears thereon at opposite ends the designations "Up" and "Down" and intermediate the designations "Up" and "Down" the plate 61 bears the designation "Float."

55 The plate 61 as shown also carries thereon a rearwardly pointing arrow 62 adjacent each designation "Up," "Float" and "Down," so that when the end face 63 is aligned with the arrow for each respective designation, there is indicated to the operator that the particular adjustment 60 of the brush with respect to the nozzle has been attained.

65 For normally maintaining the strip operating member 47 for endwise movement thereof in that portion of the slot 51 therein bounded by the end 65 53, the side portions 56 and 57 and the stop or detent portion 58, there is provided an upwardly and downwardly extending leaf spring 64 which is secured upon the rear face of the brush sheath case 27 as by the screw 30 adjacent the operating member actuating tongue 48, the upper end

of the spring 64 extending and pressing against the rear side edge of the strip operating member 47.

70 Each notch 44 of the cam plate 28 has a lower normally horizontal face 65 spaced from the preferably parallel down-locking downwardly presented latch face 66 a distance somewhat greater than the thickness of the latch catch tongues 60 of the strip operating member 47, and the leaf spring 38 tends to normally press the brush 20 75 downwardly until the collar shanks 35 of the nuts 33 abut against the bottom ends of the slots 32 of the cam plate 28, but the greater distance between the notch lower faces 65 and the latch faces 66 than the thickness of the 15 tongues 60, permits rocking of the brush 20 when in locked down position.

20 In Figs. 4 and 5 the brush 20, the spring 38, the operating member 47, the cam plate 28, and the associated parts thereof, are shown in their 25 respective positions when the brush is in floating position with respect to the nozzle entrance mouth 24, and in which position of adjustment the brush is free to rock and to move upwardly and downwardly, the collar shanks 35 on the 25 brush 20 having clearance in the slots 32 of the cam plate 28 move upwardly and downwardly and/or rock therein, and the latch catch tongues 60 of the operating member 47 are clear of all faces or edges of the notches 44 as shown in 30 Fig. 4.

35 The floating position of the brush 20 with respect to the nozzle entrance mouth 24 is the usual position thereof under most conditions of use of the suction cleaner 10.

40 When it is desired that the brush shall be adjusted to the locked up position with respect to the nozzle, the operating member 47 is moved longitudinally endwise from its position as shown in Figs. 4 and 5 to its position as shown in Figs. 40 6 and 7, during which the side edges of the latch catch tongue 60 adjacent the brush raising cam faces 42 are moved against the same and ride upon the same elevating the brush, and then the bottoms of the latch catch tongues 60 ride 45 across the up-locking upwardly presented latch faces 43 of the cam plate 38, against the downwardly urging action of the spring 38.

50 For alternately selecting the locked up position or the floating position of the brush, the operating member 47 is moved longitudinally endwise, with the straight slot 49 guiding on the shank of its screw 50, and with the portions of the slot 51 bounded by the end 53, the side portions 56 and 57, and the stop or detent portion 58, guiding and limiting the movement of the operating member 47 on the shank of the associated screw 41.

55 In other words, opposite lateral thrusts applied by the operator or user on the actuating tongue 48, and which may be applied by the foot of the operator, are all that are required to selectively position the brush 20 in either the floating or locked up position with respect to the nozzle mouth 24, the stop or detent portion 58 abutting 60 against the shank of the associated screw 41 serving to effectively prevent undesired movement of the operating member 47 beyond the floating position to the locked down position, the spring 64 urging the operating member 47 so that the angled stop or detent portion 58 of the slot 51 abuts against the shank of the associated screw 41 when the operating member 47 is in the "Float" position as shown in Fig. 5.

65 When however it is desired to adjust the brush 20 to the locked down position, it is necessary 70 75

for the user to manually grasp the actuating tongue 48 of the strip operating member 47 and to pivot the strip 47 on the shank of the screw 50 laterally rearwardly against the spring 64 so as to swing the angled stop portions 58 and 59 of the slot 51 across the shank of the associated screw 41 and to position thereon that portion of the slot 51 bounded by the stop or detent portion 59, the side portions 54 and 55 and the end portion 52, and then to move the operating member 47 endwise away from the "Float" and "Up" position thereof to the "Down" position as shown in Figs. 8 and 9, in which position the latch catch tongues 60 of the operating member 47 will be located in the notches 44 of the cam plate 28 beneath the down-locking downwardly presented latch faces 45 so that the brush 20 is maintained in the locked down position with respect to the nozzle, for use for example on rugs having a long nap and a heavy accumulation of dirt.

It is to be noted that in any of the three selectively adjustable positions of the brush 20 with respect to the nozzle 24 in the present improvements, that the brush 20 can always rock about its longitudinal axis, which not only serves to provide for self-cleaning of the brush 20 during use, but also for automatic self-rocking adjustments thereof, when different adjustments are made in the position of the nozzle entrance 30 mouth 24 with respect to the surface over which it is being used.

The slot 51 as above described may be otherwise defined for convenience as comprising a slot having offset straight sided portions connected with each other by angled stop side portions.

The embodiments of the present improvements illustrated and described herein are by way of example, and the scope of the present invention is not limited to the same or to the particular details thereof, but is commensurate with any and all novel subject matter contained herein which may at any time properly under the United States patent laws be set forth in claims hereof or originating herein, the elements of any of such claims being intended to include their reasonable equivalents.

I claim:

1. In adjustable brush construction, a brush, mounting means for the brush including a plate, and selective adjusting means operatively associated with the brush and including cam and latch faces formed on the plate and an operating member having cam follower and latch catch means for cooperation with the cam and latch faces of the plate, the operating member being arranged for selective longitudinal movements on the brush between two positions and also for selective additional lateral and longitudinal movement on the brush between one of the first two positions and a third position, the movement of the operating member between the first two positions serving alternately by cooperation of the cam follower and catch means and certain cam and latch faces to adjust the brush with respect to the mounting means in two different conditions, and the selective additional movement of the operating member between one of the first two positions and the third position serving alternately by further cooperation of the cam follower and catch means and other cam and latch faces to adjust the brush with respect to the mounting means between one of the first two conditions and a third condition.

2. In adjustable brush construction, a brush, means mounting the brush for different selective

conditions of adjustment including a plate, and selective adjusting means including an operating member cooperatively associated with the plate and mounted on the brush and operative by longitudinal movement with respect to the brush for selectively adjusting the brush to different conditions of adjustment with respect to the plate, the adjusting means also including stop means associated with the operating member and normally preventing longitudinal movement of the operating member in one direction at an intermediate position of adjustment thereof, the operating member being arranged for selective movements on the brush between a plurality of positions with respect to the stop means, each position of the operating member serving to adjust the brush in a selected condition of adjustment with respect to the plate different from the condition of adjustment of the brush corresponding to any other position of the operating member.

3. In adjustable brush construction, a brush, mounting means for the brush, and selective adjusting means operatively associated with the brush and including a longitudinally and pivotally movable operating member arranged for selective longitudinal movement with respect to the brush between two positions and also for pivotal movement and then selective additional longitudinal movement with respect to the brush between one of the first two positions and a third position, the longitudinal movement of the operating member between the first two positions serving alternately to adjust the brush with respect to the mounting means in two different conditions, and the selective additional pivotal and longitudinal movement of the operating member between one of the first two positions and the third position serving alternately to adjust the brush with respect to the mounting means between one of the first two conditions and a third condition.

4. In adjustable brush construction, a brush, mounting means for the brush, and selective adjusting means operatively associated with the brush and including a longitudinally and pivotally movable operating member arranged for selective longitudinal movement with respect to the brush between two positions and also for pivotal movement and then selective additional longitudinal movement with respect to the brush between one of the first two positions and a third position, the adjusting means also including stop means associated with the operating member and determining the position of the operating member for pivotal movement, the longitudinal movement of the operating member between the first two positions serving alternately to adjust the brush with respect to the mounting means in two different conditions, and the selective additional pivotal and longitudinal movement of the operating member between one of the first two positions and the third position serving alternately to adjust the brush with respect to the mounting means between one of the first two conditions and a third condition.

5. In adjustable brush construction, a brush, means mounting the brush for different selective conditions of adjustment including a plate disposed longitudinally of the brush, and selective adjusting means including an operating member movable longitudinally and pivotally on the brush and cooperatively interposed between the brush and the plate and operative by longitudinal movement on the brush or pivotal and longitudinal movement with respect to the brush to select-

tively adjust the brush to different conditions of adjustment with respect to the plate.

6. In adjustable brush construction, a brush, means mounting the brush for different selective conditions of adjustment including a plate disposed longitudinally of the brush, and selective adjusting means including an operating member movable longitudinally and pivotally on the brush and cooperatively interposed between the brush and the plate and operative by longitudinal movement on the brush or pivotal and longitudinal movement with respect to the brush to selectively adjust the brush to different conditions of adjustment with respect to the plate, and spring means controlling pivotal movement of the operating member.

7. In suction cleaner nozzle and adjustable brush construction, a nozzle having an intake mouth, a brush, means mounting the brush, on the nozzle, and selective adjusting means operatively associated with the brush and including a longitudinally and pivotally movable operating member arranged for selective longitudinal movement with respect to the brush between two positions and also for pivotal movement and then selective additional longitudinal movement with respect to the brush between one of the first two positions and a third position, the longitudinal movement of the operating member between the first two positions serving alternately to adjust the brush with respect to the nozzle in two different conditions, and the selective additional pivotal and longitudinal movement of the operating member between one of the first two positions

and the third position serving alternately to adjust the brush with respect to the nozzle between one of the first two conditions and a third condition, and spring means controlling pivotal movement of the operating member.

8. In adjustable brush construction, a brush, mounting means for the brush including a plate, and selective adjusting means operatively associated with the brush and including cam and latch faces formed on the plate and a longitudinally and pivotally movable operating member having cam follower and latch catch means for cooperation with the cam and latch faces of the plate, the operating member being arranged for selective longitudinal movement on the brush between two positions and also for selective pivotal and longitudinal movement on the brush between one of the first two positions and a third position, the movement of the operating member between the first two positions serving alternately by cooperation of the cam follower and catch means and certain cam and latch faces to adjust the brush with respect to the mounting means in two different conditions, and the selective movement of the operating member between one of the first two positions and the third position serving alternately by further cooperation of the cam follower and catch means and other cam and latch faces to adjust the brush with respect to the mounting means between one of the first two conditions and a third condition, and spring means controlling the last mentioned selective additional movement of the operating member.

EUGENE F. MARTINET.
